COMBINED ELECTRIC FAN AND BEATER

Filed July 16, 1928

Inventor:
Hugh W. Harris,
By Chindell Parker Carlson Attn:

UNITED STATES PATENT OFFICE

HUGH W. HARRIS, OF CHICAGO, ILLINOIS

COMBINED ELECTRIC FAN AND BEATER

Application filed July 16, 1928. Serial No. 293,001.

The general object of the invention is to provide apparatus comprising an electric fan and means whereby the fan motor may be used to drive an appliance of the egg beater 5 or beverage mixer type. More particularly, the object of the invention is to combine the parts of the apparatus in such a way as to reduce to a minimum the manipulations required in converting the apparatus 10 from one use to the other.

In the accompanying drawings:

Figure 1 is a side elevation of an apparatus embodying the features of my invention, the apparatus being shown as arranged 15 for use as a beater or mixer.

Fig. 2 is a fragmental view of the apparatus in use as an electric fan.

Fig. 3 is a sectional view of a coupling element connected to the fan. 20 Fig. 4 is a similar view of a coupling element connected to the beater or mixer.

Fig. 5 is a fragmental face view of the fan guard showing the coupling attached to the fan and certain cooperating parts.

25 The framework of the apparatus comprises a base 1 of any preferred size and shape adapted to be mounted upon the wall. Rigidly secured to the upper part of said base is an electric fan which may be of the conventional or any preferred construction. Herein it is shown as comprising a base 2 which is secured to the base 1. The electric motor 3 is pivoted to the base 2 on the axis 4 and may be secured in the desired angular 30 adjustment by means of a thumb nut 5. On the base 2 is a projection 2^a arranged to engage the housing of the motor 3 when the latter is adjusted to the position shown in Fig. 1. The armature shaft 6 carries fan blades 7.

To the forward end of the shaft 6 is rigidly secured a coupling member in the form of a sleeve 8 having an open forward end, said sleeve having two diametrically opposite longitudinally-extending slots 9. 10 is a shaft having upon one end a ball 11 adapted to fit within the sleeve 8, said ball having two diametrically opposite studs 12 adapted to fit within the slots 9 and thus cause the shaft 10 to revolve with the motor 45 shaft 6.

13 is a fan guard of ordinary construction secured to the housing of the motor 3. The coupling 8 projects out of the fan guard. Two sheet metal members 14 are secured to the central forward portion of the fan guard, 55 said members being spaced apart so as to provide between them a space or slot 15 which lies in a vertical plane. The slot 15 is wide enough to allow the shaft 10 to pass through it freely, but is not large enough to permit 60 the passage of the ball 11, hence the members 14 serve as a means for retaining the shaft 10 in association with the electric fan when the shaft is disengaged from the coupling 8.

65 On the lower portion of the base 1 is means for supporting a container in which materials are to be mixed or agitated. While the support may be of any preferred character, I have herein shown it as consisting of a 70 sheet metal ring 16 in which a tapering container 17 may be set.

The mixing or agitating device is in the form of a unit 18 which may partake of various forms within the scope of this invention. Herein the unit is shown as comprising a cover 19 adapted to rest upon and close the upper end of the container 17. Rising from the cover 19 is a bracket 20 to which is fixed a horizontally extending bracket 21. 75 On the forward end of the bracket 21 are two bearings 22 and 23 for a vertical shaft 24. To the upper end of the shaft 24 is fixed a coupling 25 in the form of a sleeve having an open upper end, said sleeve having 80 one or more pairs of diametrically opposite longitudinal slots 26. The lower end of the shaft 10 has fixed thereto a ball 27 adapted to fit within the coupling 25, said ball having two diametrically opposite pins 28 adapted 85 to fit within the slots 26. To the rear end of the bracket 21 is secured a handle 29. 90 30 is a stop portion connected to the framework of the apparatus and projecting upwardly into position to lie alongside the handle 29, said stop being so located that when the handle 29 lies alongside the stop the shaft 24 is aligned with the motor shaft 6. A gear wheel 31 fixed to the lower end of the shaft 24 meshes with a gear wheel 32 fixed to a 95 100

beater element 33. The gear 32 in turn meshes with a gear 34 which is fixed to a similar beater element 35. The beater elements 33 and 35 are rotatably mounted upon a frame 36 which is rigidly secured to the bracket 21.

5 The switch for controlling the operation of the motor is enclosed within the base 2, as usual, and may be of the ordinary form providing for variable speeds. The switch is 10 operated by means of a hand lever 37 located in the base 2 adjacent to the base 1.

When the fan occupies the position shown in Fig. 1, the fan blades are relatively close to the switch-operating lever 37. In order to 15 protect the operator's hand from contact with the fan blades when reaching under or around the fan guard to operate the switch lever, wire netting 38 may be secured to the fan guard in position to cover those portions 20 of the fan guard which are near the switch lever when the motor shaft is in vertical position, namely, the bottom, rear and side portions of the fan guard, reference being had to the position shown in Fig. 1.

25 Fig. 1 shows the parts arranged for use in beating eggs, mixing a beverage, or the like. The rotation of the shaft 10 tends to hold the handle 29 against the stop 30. When the mixing has been completed, the switch 37 is operated to stop the motor and the shaft 10 is slid upwardly until the ball 27 is free of the coupling 25, whereupon the unit 18 may be lifted off the container and the latter removed from the support 16.

30 35 When the apparatus is to be used as an electric fan the fan is swung on its axis 4 into the position shown in Fig. 2, the shaft 10 being withdrawn from engagement with the coupling 8 and allowed to hang from the members 14, as shown in Fig. 2.

40 It will be seen that the shaft 10 which communicates power from the fan to the agitating unit 21 is permanently connected to the fan so that there is no possibility of mislaying or losing the shaft. Moreover, the means for 45 connecting the shaft to the motor and to the mixing unit is of such nature that the shaft may be coupled and uncoupled very easily and quickly. As will be evident, the conversion of the apparatus from one use to the other requires a minimum number of operations and all of these are of a very simple kind so that the apparatus may be operated safely and effectively by persons unskilled in the 50 use of tools or machinery.

55 In the following claims, the term "beater unit" is used to denote a unit intended for beating eggs and other material, mixing beverages, etc.

60 I claim as my invention:

65 1. The combination of a base, an electric motor mounted on said base for adjustment into horizontal and vertical positions, a coupling on the motor, a support on said base below the motor, a receptacle on said

support, a beater unit adapted to rest upon said receptacle, said unit comprising an upwardly extending coupling, a shaft adapted at its ends for engagement with said couplings, and a retainer on the motor to support the upper end of the shaft when the latter is disengaged from the motor coupling.

70 2. The combination of a base, an electric motor mounted on said base for adjustment into horizontal and vertical positions, a coupling on the motor, a receptacle below the motor, a beater unit adapted to rest upon said receptacle, said unit comprising an upwardly extending coupling, and a shaft adapted at its ends for engagement with said 75 couplings.

80 85 3. The combination of a base, an electric motor mounted on said base for adjustment into horizontal and vertical positions, a support on said base below the motor, a receptacle on said support, a beater unit adapted to rest upon said receptacle, and detachable means for communicating power from the motor to the beater unit.

90 4. In combination, a base, an electric motor on the base, a beater unit having a coupling, a coupling on the motor, a shaft adapted at its ends for connection to said couplings, and a retainer on the electric motor to support said shaft when the latter is detached from the motor coupling.

95 5. In combination, an electric motor, a beater unit having a coupling, a coupling on the motor, and a shaft adapted at its ends for connection to said couplings.

100 105 6. In combination, a support, a receptacle adapted to rest on the support, a beater unit including a cover adapted to rest removably on the receptacle, said unit comprising a revoluble beater element attached to and suspended from the cover, and driving means having a detachable driving connection with said element.

110 In testimony whereof, I have hereunto affixed my signature.

HUGH W. HARRIS.
